UNITED STATES PATENT OFFICE.

JAMES HUMPHREY, OF BOSTON, MASSACHUSETTS, ASSIGNOR TO PERRY MASON COMPANY, A CORPORATION OF MASSACHUSETTS.

OFFSET-CLEANER.

SPECIFICATION forming part of Letters Patent No. 761,633, dated May 31, 1904.

Application filed April 16, 1903. Serial No. 152,824. (No model.)

To all whom it may concern:

Be it known that I, JAMES HUMPHREY, a citizen of the United States, and a resident of the city of Boston, in the county of Suffolk, State 5 of Massachusetts, have invented certain new and useful Improvements in Offset-Cleaners, of which the following is a full, clear, and exact description.

In the usual type of rotary presses it is customary to provide the impression-cylinder with a movable offset-sheet for the purpose of preventing smearing by the green ink of the freshly-printed paper. Even with frequent shifting of such sheet, however, it is still quite difficult to keep the printed paper perfectly clean and clear from offset; and it is the object of this invention to construct an improved means for removing more or less of the offset-ink from the offset-sheet as rapidly 20 as it accumulates thereon.

Referring to the drawings forming part of this specification, Figure 1 is a side elevation of my apparatus and of the cylindrical impression member with which it is connected. 25 Fig. 2 is a side sectional view of the same on the line X X in Fig. 4. Fig. 3 is a side sectional view of the same on the line Y Y in Fig. 4; and Fig. 4 is a plan view of my apparatus, but with part thereof broken away.

30 The impression-cylinder is designated by the reference character 1 and is mounted in the usual manner upon a shaft 2, supported by the machine-framework 4. Upon this cylinder and the usual offset-sheet covering it 35 and just in contact with such sheet is the composition roll 10, whose shaft 11 is supported in bearings 15, held in the boxes 16 and vertically adjustable by means of the set-screws 17. Hence by turning said screws the bearings 40 can be adjusted to properly vary the contact of the roll with the offset-sheet or to move it out of contact wholly when desired. The ear 18 being swung to one side, the bearing 15 can be removed and the roll withdrawn 45 whenever needed. Kept in suitable contact with said roll by a similar arrangement of bearings and boxes is the roller 20, formed of any suitable material, as wood, and covered with sheet-felt 22 of moderate thickness. In

contact with this roller is a similar roller 30, 50 covered with a sheet of felt 32 and supported in similar adjustable bearings. The latter roller 30 dips into a tray 40, kept partially filled with naphtha or other ink-dissolving liquid, and its felt cover 32 becoming saturated 55 therewith and being properly rotated the liquid is conveyed to the felt cover 22 of the other roller. To thus rotate the said rollers, I provide the lever 50, fulcrumed upon the end of the shaft 21 and oscillated by the pin 60 52, projecting from the shaft 2 into the slot 51 of such lever. At the upper end of this lever is a pawl 52, engaging the teeth of the gear-wheel 54, which is fixed on said shaft 21. Hence as the cylinder 1 revolves the 65 roller 20 is slowly and intermittently rotated. In a similar manner the roller 30 is slowly turned, the lever 55 being fulcrumed on the shaft 31, provided at its upper end with a pawl 57, engaging the gear-wheel 58, fixed on 70 the shaft 31 and coupled to the lever 50 by a connecting-rod 56. Said two pawls are, it will be seen from Fig. 1, made to face in opposite directions in order to cause their respective rollers to be turned in opposite directions. Moreover, the distance of the rod 56 from the shaft 21 being double that from the shaft 31 as measured on the respective levers 50 55, the lever 55 will be given twice 75 the amplitude of oscillation of the other. Hence the pawl 57 will traverse twice the number of gear-teeth as does the pawl 53, and the roller 30 will accordingly move twice as fast as its neighbor. Inasmuch as the said rollers are turned intermittently and in different directions and speed by the pawls, I find it necessary to provide a means for preventing one from moving the other. To do this, I provide the friction device, comprising the two wooden clamping members 25 35, pivoted 80 together at 27. This device is shown more fully in Fig. 2, where the shaft 21 is shown as embraced between the two clamping-sections 25 26, pressed together and against such shaft by the set-nuts 28, and the clamping-sections 35 36, similarly pressed against the shaft 31 by the set-nuts 37. 85 90 95

In operation the composition roll 10 re-

volves rapidly by its frictional contact with the impression-cylinder and takes upon its surface the ink offset upon the offset-sheet. As this roll turns in contact with the naphtha-
moistened felt 22 of the roll 20 all the ink taken up by said roll is removed therefrom by the felt. As the roller 20 slowly revolves a fresh section of moistened felt is constantly presented to the roll and in its turn becomes loaded with ink. When this soiled felt 22 revolves into contact with the felt 32 of the roller 30, this latter felt, being freshly charged with naphtha and moving with faster motion in contact with the soiled felt, soon removes from the latter the greater part of its ink. The further rotation of the roller 30 then carries the soiled felt 32 over and down into the tray 40 and is thoroughly cleansed by its passage through the naphtha.

To prevent too much of the liquid being carried up by the felt 32, I provide the metal blade 42, pivotally supported at its lower edge and resting against the felt 32, as shown in Figs. 2 and 3.

What I claim as my invention, and for which I desire Letters Patent, is as follows, to wit:

1. The combination with the impression-surface of a printing-press, of a composition roll resting thereon, an absorbent roll located parallel to the latter but out of contact with both it and said impression-surface, a tray inclosing the lower part of the last-named roll and containing an ink-dissolving fluid, and an absorbent-surfaced roller contacting with both said rolls, substantially as described.
2. The combination with the impression-surface of a printing-press, of a composition roll resting thereon, an absorbent-surfaced roll located parallel with the latter but out of contact with both it and said impression-surface, a tray inclosing the lower part of the last-named roll and containing an ink-dissolving fluid, an absorbent-surfaced roller contacting with both said rolls and turned at a different speed from either of the latter, substantially as described.
3. The combination with the impression-cylinder, of a composition roll contacting

therewith, an absorbent-surfaced roller revolvable in contact with said roll, a gear-wheel 50 rigid with said roller, a lever pivoted upon the shaft of said roller and having at its upper end a pawl engaging said gear-wheel, a crank-pin engaging said lever and moving with the shaft of said cylinder, a second absorbent-surfaced roller revolvable in contact with the first-named one, a gear-wheel rigid with said second roller, a lever pivoted on the shaft of the latter and having at its upper end a pawl engaging the last-named gear-wheel, a connecting-rod joining said levers, and a fluid-containing tray inclosing the lower part of the last-named roller, substantially as described.

4. The combination with the impression-surface of a printing-press, of the composition roll in contact therewith, the two absorbent-surfaced rollers in contact with each other, and one thereof contacting with said roll and the other being supplied with an ink-dissolving fluid, means for intermittently and differently rotating said rollers, such means including pawls and gear-wheels, and a friction device for said rollers comprising wooden clutch members clamped about the shafts thereof and secured the one to the other, substantially as described.

5. The combination with the impression-surface of a printing-press, of a composition roll contacting therewith, two absorbent-surfaced rollers contacting with each other and one thereof with said roll, a naphtha-containing tray located beneath the other of said rollers and moistening the surface thereof with its contents, means for rotating said rollers, and the blade pivoted along its lower edge 85 in said tray and having its upper edge resting against the surface of the roller in said tray, substantially as described.

In testimony that I claim the foregoing invention I have hereunto set my hand this 14th 90 day of April, 1903.

JAMES HUMPHREY.
